UNITED STATES PATENT OFFICE

ELI GLASSER, OF BROOKLYN, NEW YORK

DESIGN FOR A BREAD BOX

Application filed January 22, 1931. Serial No. 38,410. Term of patent 14 years.

To all whom it may concern:

Be it known that I, ELI GLASSER, a citizen of the United States, residing at Brooklyn, county of Kings, and State of New York, have invented a new, original, and ornamental Design for Bread Boxes, of which the following is a specification, reference being had to the accompanying drawings, forming part thereof.

Fig. 1 is front elevation, Fig. 2 is an end elevation and Fig. 3 is a top plan view of a bread box showing my new design.

I claim:

The ornamental design for a bread box as shown.

ELI GLASSER.
